[57] **ABSTRACT**

A sight mounting pad is pivotally mounted on the spherical heads of a pair of longitudinally spaced bolts and is secured to a supporting member by four machine bolts two of which are mounted through the mounting pad and supporting member on opposite sides of each of the spherical headed bolts. The spherical headed bolts are adjusted vertically to level the mounting pad longitudinally and by loosening two of the machine bolts on one side of the spherical headed bolts, and tightening the two machine bolts on the other side thereof, the mounting pad is levelled transversely.

ADJUSTABLE MOUNT FOR AUXILIARY GUN SIGHT

BACKGROUND OF THE INVENTION

This invention relates to sights and pertains more particularly to means for adjustably mounting a sight to a supporting gun. A problem has developed in the matter of mounting an auxiliary sight to the gun in a weapon system so as to be in alignment with the primary sight system thereof where the member which supports the primary sight is a roughly surfaced casting.

SUMMARY OF THE INVENTION

The problem has been successfully overcome with the present invention whereby the mounting pad for the auxiliary sight is located on the supporting member relative to the bars which index the primary sight and are mounted on a pair of spherical headed bolts for pivotal displacement. Four machine bolts two of which are mounted through the mounting pads and supporting member on opposite sides of each of the spherical headed bolts secure the mounting pads thereto. The spherical headed bolts are screwed up and down by a screw driver to level the mounting pads longitudinally and by loosening two of the machine bolts on one side of the spherical headed bolts and tightening those on the other side thereof the mounting pad is leveled transversely.

BRIEF DESCRIPTION OF THE DRAWING

FIG. 1 is a fragmentary top view of a sight mounting pad assembled to the sight support casting;

FIG. 2 is a cross-sectional view taken along line 2—2 of FIG. 1; and

FIG. 3 is a cross-sectional view taken along line 3—3 of FIG. 1.

DESCRIPTION OF A PREFERRED EMBODIMENT

Shown in the drawing is a sight support casting 12 for weapons systems such as those that include a Vulcan gun, which casting is adapted for assembly to the gun so as to support a lead computing sight (not shown). Casting 12 comprises a pair of longitudinally spaced and vertically disposed flanges 14 which are integrally connected along the top and at opposite ends by a web 16. Provided in each of the flanges 14 is a recess 20 which receives the lead computing sight (not shown) and shown extending between the flanges is one of two bars 22 for supporting and locating the lead computing sight. Bars 22 are of square configuration in cross-section and, when casting 12 is assembled to the supporting gun, they are located parallel to the bore axes of the gun barrels so that the lead computing sight (not shown) is aligned therewith.

When an auxiliary sight is to be added to the weapon system, means must be provided, because of the surface roughness of casting 12, for mounting it thereto so that it is firmly seated and so that it can be adjusted into alignment with the line of sight of the gun barrels. This is accomplished by mounting as hereinafter described to the top side of web 16 a clamping plate 24 with a front backplate 26 and a rear backplate 28 located under the web opposite the front and rear ends of the clamping plate respectively.

Located symmetrically in opposite ends of clamping plates 24, so as to extend downwardly and integrally therefrom, is a stud 32. Each of the studs 32 is provided therethrough with a threaded axial bore 36 which extends through clamping plate 24 and each of the studs is threaded externally at 34. Studs 32 are receivable by mating holes 37 located in web 16 equidistant from bar 22 so that clamping plate 24 is thereby located parallel thereto. Studs 32 also extend through mating orifices 38 in the respective front backplate 26 and rear backplate 28 and a nut 40 engages each of the external threads 34 so that when tightened against the respective front and rear backplate clamping plate 24 is secured against displacement to web 16, as shown in FIGS. 2 and 3.

A bolt 42 having a spherical head 44 with a screw driver slot 46 therein is threaded downwardly into each of the bores 36 so that a portion 48 of the bolt extends from the bottom end of the respective stud 32. A locking nut 49 is threaded onto extending portion 48 of each of the bolts 42 and tightened against the end of the associated stud 32 to secure the bolt in a vertically adjusted position relative thereto. Heads 44, which are located above the top surface of the clamping plates 24, provide bearings for the pivotal displacement of a mounting pad 50, as hereinafter described. Mounting pad 50 is secured to clamping plate 24 by means of four machine bolts 52 two of which extend vertically through the mounting pad, clamping plate 24, web 16 and either front backplate 26 or rear backplate 28 on opposite sides of each of the studs 32. Nuts 53 are threaded on the end of each of the machine bolts 52 to secure mounting pads to clamping plates 24 when tightened. Heads 44 are received by mating spherical recesses 54 formed in the bottom of mounting pads 50 to provide pivotal seats therefor and apertures 56, communicating with recesses 54, permit entry of a screw driver thereinto for engagement with screw driver slots 46 in the heads for turning bolts 42 to raise or lower the heads relative to clamping plates 24. Suitable means, as bracket 58, are provided on mounting pad 56 for mounting an auxiliary sight thereto.

To level mounting pad 50 longitudinally, nuts 53 on bolts 52 and locking nuts 49 on bolts 42 are loosened and then bolts 42 can be screwed up or down by a screw driver or other suitable tool inserted through apertures 56 for engagement with screw driver slots 46 and heads 44. When nuts 49 are retightened, bolts 42 and heads 44 thereon are secured in their adjusted vertical positions and when nuts 53 are retightened mounting pad 50 is secured in its adjusted position. Mounting pad 50 is leveled transversely by loosening nuts 53 on those bolts 52 which are positioned on one side of studs 32 and tightening the nuts on those bolts which are located on the opposite side of the studs.

I wish it to be understood that I do not desire to be limited to the exact details of construction shown and described, for obvious modifications will occur to a person skilled in the art.

I claim:

1. The combination comprising a gun sight supporting member, a clamping plate, a pair of longitudinally spaced bolts threadingly engaged with said clamping plate for vertical adjustment relative thereto, each of said bolts including a spherical head and means for vertical adjustment thereof, a mounting pad including a pair of spherical recesses for receiving said heads in bearing contact to pivotally mount said mounting pad relative to said clamping plate, means for securing said mounting pad and said clamping plate to said sight supporting member and effecting transverse leveling of said mounting pad relative thereto about said heads, and an aperture communicating with each of said recesses to permit access to said heads for vertical adjustment thereof to level said mounting pad longitudinally relative to said sight supporting member.

2. The combination as defined in claim 1 wherein said clamping plate comprises a pair of studs extending therefrom through mating holes located in said sight supporting member equidistant from a gun barrel oriented supporting bar therein, a threaded axial bore through each of said studs and said clamping bar for threadingly receiving one of said bolts, and a nut threadingly mounted on each of said studs so as to secure said clamping plate to said sight supporting member when tightened.

3. The combination as defined in claim 1 wherein said means comprises four machine bolts with engaging nuts extending through cooperating holes in said mounting pad, said sight supporting member and said clamping plate for securing said mounting pad thereto responsive to tightening of said nuts on said machine bolts, two of said machine bolts being located on opposite sides of each of said studs to effect transverse leveling of said mounting pad when said machine bolts are vertically adjusted.
